KEY CONTAINER

Clifford Kirkpatrick, Minneapolis, Minn.

Application February 20, 1939, Serial No. 257,398

5 Claims. (Cl. 70—456)

My invention provides a simple and highly efficient key container adapted to normally encase a plurality of keys combined with means for selectively projecting the keys from the casing.

Generally stated, the invention consists of the novel devices, combination of devices and arrangement of parts herein described and defined in the claims.

In this improved arrangement the keys are normally confined within the casing and each key has its own carrier, which when selected and properly moved, projects the particular key out of the casing ready for use.

In the accompanying drawing which illustrates the invention in its preferred form, like characters indicate like parts throughout the several views.

Referring to the drawing:

Fig. 1 is a perspective showing the complete device;

Fig. 2 shows the device held in the hands of an operator with one key projected for use;

Fig. 3 is a section taken on the line 3—3 of Fig. 1;

Fig. 4 is a section taken on the line 4—4 of Fig. 1;

Fig. 5 is a fragmentary section showing parts of the casing on the line 5—5 of Fig. 1;

Fig. 6 is a fragmentary section with some parts sectioned on the line 6—6 of Fig. 3;

Fig. 7 shows one of the keys and its carrier removed from the casing;

Fig. 8 is a perspective showing one of the key carriers; and

Fig. 9 is a perspective showing one of the spacer washers.

The casing 10 is preferably a light sheet metal structure comprising flat parallel sides and connecting portions, the latter being formed with parallel key passages or slots 11. Both the upper and lower portions of the casing are rounded, the upper portion being of larger diameter, and the front and rear walls being connected to the curved upper and lower portions. Extended transversely through the curved or semi-cylindrical upper portion of the casing, is a non-rotary shaft or spindle 12 that is fixed to the side walls of the casing and held against rotation.

Rotatably mounted on the spindle 12 is a plurality of key carriers, each of which is made up of laterally spaced spring metal plates 13 having projecting arms 14 terminated in heads or the like 15 which, in practice, will be marked some

way to indicate the character of the key held by the particular key carrier. As best shown in Fig. 2, these key carriers, in side elevation, are of bell-shaped form, that is, the arms 14 project from the spring plates 13, in the planes thereof and at approximately right angles thereto.

Between the several key carriers are spacing washers 16 that freely slide on the spindle 12 but are held against rotation by suitable means such as key lugs 17 on the said washers that work in a groove 18 in said spindle 12.

Yielding means, preferably in the form of a small coil spring, is placed on the spindle 12 and compressed between the adjacent side of the casing 10 and the key carriers. This spring frictionally presses the several key carriers together and keeps the plates 13 thereof pressed frictionally against the respective keys. The keys are indicated by the character K, and these keys are provided with the customary perforations 20 in their heads that adapt them to be pivotally mounted on inwardly pressed trunnions or lugs 20. With this arrangement the keys can be readily sprung into or out of pivotal engagement with the spring plates of the respective key carriers; and when the keys are thus applied, they will be capable of pivotal movement on the trunnions 20 but will be frictionally held against such pivotal movement and will be positively held against lateral swaying movements and, hence, 30 in proper alignment with the respective key passages or slots 11. In their hubs the plates 13 are formed with holes 21 that adapt them to be slid on to the non-rotary spindle 12.

The heads 15 of the key carriers will be located just outside of the slots or key passages 10 where they may be readily engaged by the finger and moved from full line to dotted line position in Fig. 3 and conversely. The keys are preferably spring clamped by the plates of 40 the key carriers so that they will be held in line with the clamping plates and will be projected as shown by dotted lines in Fig. 3. The slots 11 extend not only to the front side but over the crown of the casing so that the keys can be projected as shown by dotted lines in Fig. 3.

It is sometimes desirable to provide the casing with a pivoted door 22. This door 22, as shown, is pivoted to the casing at 23 and has frictional engagement therewith at 24.

The device described, while efficient for the purposes had in view, may be produced at comparatively small cost. While the preferred form thereof has been illustrated, it will be understood that the device as illustrated is capable of modi-

fication within the spirit of the invention herein disclosed and claimed.

What I claim is:

1. A device of the kind described comprising a casing, a non-rotary spindle extended through said casing, and a plurality of key carriers independently mounted directly on said non-rotary spindle and provided at their extended portions with means for holding and carrying keys, the said key carriers having projecting arms adapting them to be independently manipulated from the exterior of the casing, said key carriers each comprising a pair of spring plates having inwardly pressed trunnion-forming portions engageable in holes in the head of the keys.
2. In a device of the kind described, a casing, a common spindle extended within said casing, and a plurality of key carriers independently pivoted on said common spindle and having projecting arms adapting them to be independently manipulated, said key carriers further having radially projecting key holders engageable with the heads of the keys at points remote from the axis of said spindle and adapted to carry the keys bodily on the arc of a circle, the axis of which is the axis of said spindle.
3. The structure defined in claim 2 in which said key holders, remote from the axis of said

spindle, have bosses adapted to engage seats in the heads of the keys.

4. In a device of the kind described, a casing, a common spindle extended within said casing, and a plurality of key carriers independently pivoted on said common spindle, said carriers having projecting arms adapting them to be independently moved pivotally on said spindle, said carriers further having projecting arms equipped with means located offset of the axis of said spindle and operative to independently and detachably hold the respective keys projected from the axis of the spindle and with the keys located entirely outward of the axis of the spindle.
5. In a device of the kind described, a casing, a common spindle extended within said casing, and a plurality of key carriers independently pivoted on said common spindle and having projecting arms adapting them to be independently manipulated, said key carriers further having spring-acting key clamping elements adapted by friction to hold the respective keys projecting radially from the axis of said spindle and for movement of said keys bodily around the axis of said spindle when the respective key carriers are moved on the axis of said spindle.

CLIFFORD KIRKPATRICK.
